(57) **CLAIM**

The ornamental design for a support for a table for trains as shown and described.

DESCRIPTION

FIG. 1 is a top perspective view of a support for a table for trains;

FIG. 2 is a front view thereof;

FIG. 3 is a right side view thereof;

FIG. 4 is a top view thereof;

FIG. 5 is a bottom view thereof;

FIG. 6 is a left side view thereof; and,

FIG. 7 is a top perspective view thereof.

The broken lines shown in the figures represent portions of a support for a table for trains that form no part of the claimed design.
